UNITED STATES PATENT OFFICE

111,170

DESIGN FOR A WINDOW CLEANING BRUSH

Frances Rogers Brown, Watertown, N. Y.

Application December 23, 1937, Serial No. 73,837

Term of patent 14 years

To all whom it may concern:

Be it known that I, Frances Rogers Brown, a citizen of the United States of America, residing at Watertown, in the county of Jefferson and State of New York, have invented a new, original, and ornamental Design for a Window Cleaning Brush, of which the following is a specification, reference being had to the accompanying drawing, forming a part thereof.

In the drawing, Figure 1 is a plan view of a window cleaning brush, showing my new design, and

Figure 2 is a fragmentary end elevational view of the bristle portion of the brush head with the adjacent portion of the frame of the head broken away.

The design is characterized by an elongated

wire handle having an intermediate twisted portion, a relatively narrow hand grip of triangular formation extending from one end of the twisted portion and comprising straight sides and an outer straight connecting end, the brush head extending directly from the other end of the twisted portion and being of triangular formation with widely diverging straight sides and a cylindrical brush connecting the outer ends of the sides and having ends extending beyond the sides of the triangular head with terminal end portions parallel with the sides of the head.

I claim:—

The ornamental design for a window cleaning brush, as shown and described.

FRANCES ROGERS BROWN.
